UNITED STATES PATENT OFFICE

105,895

DESIGN FOR A MINIATURE REFRESHMENT BAR

Jean Brown Richardson, New York, N. Y.

Application July 3, 1937, Serial No. 70,257

Term of patent 7 years

To all whom it may concern:

Be it known that I, Jean Brown Richardson, a citizen of the United States and resident of New York, in the county and State of New York, have invented a new, original, and ornamental Design for a Miniature Refreshment Bar, of which the following is a specification, reference being had to the accompanying drawing, forming part thereof.

The figure is a perspective view of a miniature refreshment bar showing my new design.

I claim:

The ornamental design for a miniature refreshment bar substantially as shown.

JEAN BROWN RICHARDSON.
